UNITED STATES PATENT OFFICE

2,544,757

THREAD MARKER

Samuel Isaacs, New York, N. Y.

Application May 17, 1947, Serial No. 748,862

1 Claim. (Cl. 112—2)

1

The present invention relates to thread markers for cloth and the like and it consists in the combinations, constructions and arrangements of parts herein described and claimed.

Generally, the invention relates to an apparatus for simultaneous marking on each of a plurality of layers of fabrics or other suitable material, such as cutout parts which are intended for assembly into a completed article such as a garment. Such apparatus may be utilized for the marking of pockets, button holes, lapels and the like.

In carrying out the invention, there is provided a mechanism which will perforate and carry through a layer of cloth or the like a thread and which has means for automatically grasping the thread after it has passed through such layer and means for holding the same until the thread inserting means has been withdrawn, whereby a single or double thread is left in the layer of cloth and thereafter cut off at each individual piece of cloth to leave a short protuberance of thread whereby to mark a particular spot on such individual piece of cloth or the like.

It is accordingly an object of the invention to provide a simple mechanism for the marking of layers of cloth by means of a thread.

A further object of the invention is the provision of a mechanism of the character described which will be simple in its construction, easy to manufacture and which will be simple yet efficient in its operation.

Another object of the invention is the provision of a novel means and mechanism for the retaining of a thread in a layer of cloth or the like after the same has been forced into such layer.

A further object of the invention is the provision of a novel means for holding the layer of cloth or the like when the same is penetrated with a needle for inserting a thread therethrough.

Another object of the invention is the provision of a novel locking means for the apparatus whereby a needle may be retained at will in the cloth layers after penetration therethrough.

A further object of the invention is the provision of a manually operated means for grasping the thread after it has penetrated the layers of cloth to be marked thereby.

Another object of the invention is the provision of a novel manually operated means whereby the locking means above referred to may be released.

For further comprehension of the invention, and of the objects and advantages thereof, reference will be had to the following description and accompanying drawing, and to the appended

2

claim in which the various novel features of the invention are more particularly set forth.

In the accompanying drawing forming a material part of this disclosure:

5 Fig. 1 is a side elevational view of an embodiment of the invention.

Fig. 2 is a bottom plan view thereof.

Fig. 3 is an elevational view, partly in section, of the device shown in Fig. 1, but showing a different position of the parts.

10 Fig. 4 is a bottom plan view of the mechanism in a certain phase of its operation.

Fig. 5 is a sectional view taken along line 5—5 of Fig. 4 looking in the direction of the arrows thereof.

15 Fig. 6 is a front elevational view of the device disclosed in Fig. 1.

Fig. 7 is a rear elevational view thereof.

Fig. 8 is a top plan view of the device shown in Fig. 1.

20 Fig. 9 is a vertical sectional view of a portion of the device.

Fig. 10 is an enlarged sectional view taken along line 10—10 of Fig. 4 looking in the direction of the arrows thereof.

25 Referring more particularly to the drawing, there is shown therein a thread marking apparatus comprising a base 10, an overhanging arm 12 attached at its lower end to the back of the base 10 and terminating at its free end in a journal 13. The base 10 is provided on its under side with a plurality of reinforcing ribs 11 which are for the purpose of providing greater strength to the structure and also for the attachment of various mechanisms thereto, which mechanisms will be hereinafter more fully described.

30 To the upper side of the arm 12 there is affixed a bracket 14 to the upper end of which is pivoted, as indicated at 15, a lever comprising an outer portion 16, and an inner telescoping member 17. The outer portion 16 is fulcrumed at 18 and is provided with a handle 19 at its free end. The lever is provided with a depending arm 20 having an angular extension 21 integrally connected therewith and provided with a pair of adjustably connected pawls 22 and 23.

35 Affixed to the rear of the arm 12 and extending upwardly therefrom is a spool holder 24 and a platform 25 associated therewith and carrying an outwardly extending arm 26 to which is adjustably connected, by means of a thumbscrew 27, a thread guide 28 having a looped upper end 29. The spool holder 24 is adapted to receive a spool of thread 30 thereon, as shown in dot and dash lines in Figs. 3 and 6 which thread is

adapted to pass through the looped upper end 29 and thence through a guide member 68 having a horizontally disposed hole 69 therein for the reception of the thread.

The pawls 22 and 23 are adapted to engage ratchet teeth 31 and 42 successively upon a downward movement of the handle 19. The ratchet teeth are formed in an arm 33 which is hinged at one end, as indicated at 34, to a lever 35 and terminates in a handle portion 36 at its other end, which handle portion is provided with a protruding handle 37. A guide bracket 38 is affixed to the arm 12 by means of a pair of screws 39 and the handle portion 36 is vertically slidably supported by the guide bracket 38 so that the arm 33 may pivot slightly about its hinged end 34 within the top and bottom limits of the guide bracket 38. A spring 40 interconnects the upper screw 39 and a screw 41 carried by the arm 33 rearwardly of the guide bracket 38 to maintain the arm normally in a forward position and in a raised pivoted position against the top portion of the guide bracket 38, as shown in Fig. 1. The lever 35 is pivoted centrally, as indicated at 42, to the rear portion of the arm 12 and is adapted to have its lower end bear against a stop 43 carried by a sliding member 44 which is mounted for reciprocal movement in the base 10 upon a pair of laterally extending supports 45 and 46. A spring 47 interconnects the member 44 and the support 46 to normally urge the member rearwardly. The forward end of the member 44 has attached thereto a substantially U-shaped bracket 48, one side of which, 49, is elongated to act as a guide and the other side, 50, of which adjustably carries a hook 51.

The fulcrum 18 of the outer portion 16 of the lever is carried by an annular collar 52 on an upper cylindrical member 53 which is provided with a threaded top member 54 to which is affixed a shaft 55 and to the lower end of which is affixed a needle 56 adapted to receive the end of the thread 30 in the usual eye opening 57.

The needle 56 has its upper end secured to the bottom end of the shaft 55 by the usual coupling tube 55^a. The tube 55^a is secured to the bottom end of the shaft 55 by a set screw 55^b and the upper end of the needle 56 is secured in position in the tube 55^a by a set screw 55^c.

The upper cylindrical member 53 telescopes the upper end of a lower cylindrical member 58. The bottom portion of the lower cylindrical member 58 is projected through the journal 13 and is secured thereto by an upper lock nut 63 and a lower lock nut 64. Fixedly mounted in the bottom end of the lower cylindrical member 58 there is a bushing 58^a, see Fig. 9.

Disposed within the lower cylindrical member 58, there is a tube 59 having an outside diameter less than the inside diameter of the lower cylindrical member. The top end of the tube 59 is formed with an outwardly directed flange 59^a which slidably engages the inner face of the lower cylindrical member 58. The bottom end of the tube 59 is slidably projected through the bushing 58^a and has threadedly mounted on the bottom end thereof a presser foot 61. The presser foot 61 is locked to the end of the tube 59 by a lock nut 61^a which also engages the bottom end of the lower cylindrical member 58 limiting upward movement of the tube 59 and presser foot 61 relative to the cylindrical member 58. The tube 59 is retained in a raised position by a coil spring 62 which is engaged concentrically about the tube

59 and which operates between the adjacent faces of the bushing 58^a and the flange 59^a.

The upper cylindrical member 53 (and in turn the operating lever) is urged into a raised position relative to the lower cylindrical member 58 by a coil spring 60 which surrounds the shaft 55 and which operates between the top member 54 and the top face of the flange 59^a. The spring 60 is somewhat stronger than the spring 62 so that when the lever is pivoted downward about its pivot 15 for engaging the end of the needle 56 through a stack of cloth, the upper cylindrical member 53 and the tube 59 will move downward as a unit compressing the spring 62, until the presser foot 61 engages the top of the stack of cloth. Downward movement of the tube 59 will be stopped, but downward movement of the upper cylindrical member 53 will continue, compressing the spring 60, and causing the needle 56 to pierce the stack of cloth. When the lever is again released the springs 60 and 62 will return the parts to the normal position shown in Fig. 9.

The bracket 33 is provided with an integrally formed laterally extending handle 65 and the arm 33 is provided with the laterally extending handle 37.

In operation, it will be seen that when it is desired to mark particular spots in a stack of fabrics to be cut into, for example, garments such as coats and the like, the stack of fabrics will be placed on the base and the proper spot marked on the uppermost fabric. This spot is then positioned immediately below the needle 56 whereupon the handle 19 is brought downwardly.

When the handle 19 is moved downwardly, from the full line position shown in Fig. 1, the upper cylindrical member 53 will move downwardly carrying the needle 56 and the pressure foot 61 therewith, against the action of the spring 62. Downward movement of the pressure foot 61 will continue until it engages the topmost layer of the layers of cloth resting on the base 10, which will hold the pressure foot 61 against further downward movement. Continued downward movement of the handle 19 will cause the needle 56 to carry the thread 30 completely through the layers of cloth.

At the start of downward movement of the handle 19, the pawl 22 engages the top face of the arm 33 and rides along that top face pivoting the arm 33 downward about its hinged end 34 and against the action of the spring 40 until the pawl 22 engages the ratchet tooth 31, whereupon continued downward movement of the handle 19 causes the pawl 22 to move the arm 33 rearward against the action of the spring 40 pivoting the lever 35 about its pivot 42, causing its lower end to move forward and bear against the stop 43 of the sliding member 44, and urge the sliding member 44 forward against the action of the spring 47. As the pointed end of the needle 56 carrying the thread 30 passes through the top wall of the base, as shown in Fig. 10, the sliding member 44 will assume the full forward position, shown in dot and dash lines in Fig. 4, in which the pointed end of the hook 51 will be forward of the bottom end of the needle, having passed the needle 56 at one side thereof.

As the handle 19 nearly reaches its completely depressed position, the position shown in full lines in Fig. 3, a slight further downward movement causes the pawl 22 to ride clear of the ratchet tooth 31 freeing the arm 33 to slide forward very slightly under the influence of the spring 40, and instantly urges the pawl 23 into

the ratchet tooth 32 arresting further forward movement of the arm 33 by the spring 40. In addition to drawing the arm 33 forward, the spring 40 also urges the arm 33 upward about its hinged end 34 to retain the respective pawls and ratchet teeth engaged.

After the fully depressed position of the handle 19 is reached, it is released so that the spring 60 raises the upper cylindrical member 53. Immediately at the start of the upward motion, the pawl 22 engages the top edge of the arm 33 rearward of the ratchet tooth 31. As the pawl 22 is now disposed rearward of the pivot 15, see Fig. 3, and has a normal position forward of the pivot 15, see Fig. 1, the pawl moves in a downward arc until it passes beneath the pivot 15. As the pawl 22 immediately engages the top edge of the arm 33 its movement in a downward arc, to pass beneath the pivot 15, causes the arm 33 to be pivoted downward against the action of the spring 40 and about its hinged end 34 disengaging the ratchet tooth 32 from the pawl 23, freeing the arm 33 to be quickly urged forward by the spring 40. Simultaneously, the lever 35 is pivoted moving its bottom end away from the stop 43, freeing the sliding member 44 to be slid rearward under the tension of the spring 47, drawing the hook 51 back to the position shown in Fig. 2.

Rearward movement of the hook 51 occurs with the eyelet 57 of the needle 56 still below the base 10, so that rearward movement of the hook causes its pointed end to pass alongside of the needle 56 and pick-up one side of the loop of thread 38, which loop is formed by the downward movement of the needle 56.

The needle 56 then continues its upward movement, causing the same to be withdrawn from the layers of cloth material and the pressure foot 61 to be raised to its starting position. The thread 30 is then cut adjacent the needle 56 and the freshly cut end, at the top of the layers of cloth, is gripped and held while removing the layers of cloth from the base 10, causing the other end of the thread engaged through the layers of cloth, to slide clear of the hook 51, leaving a strand of thread engaged completely through the layers of cloth as a marker.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:

A device of the character described comprising in combination, a base upon which a pile of fabrics is to be rested, an overhanging arm attached to said base to have a free end overhanging the pile of fabrics, a lower cylindrical member fixedly mounted at its lower end on the free end of said arm and extended vertically therefrom, an upper cylindrical member sleeving said lower cylindrical member, resilient means urging said upper cylindrical member into a raised position with relation to said lower cylindrical member, a shaft having its upper end attached to said upper cylindrical member and its lower end extended slidably through and slightly from the bottom end of said lower cylindrical member, a needle mounted on the lower end of said shaft to carry a thread therein, means for lowering said upper cylindrical member and said shaft against the action of said resilient means to extend the needle and the thread carried thereby through the pile of fabrics on said base, means for catching and holding the thread, said means for catching the thread comprising a slidably mounted arm having a pair of ratchet teeth, a vertical lever pivotally mounted on said overhanging arm and having its upper end pivotally attached to one end of said slidably mounted arm, a member slidably mounted in said base and integrally formed with a forked end, a hook carried by one end of said forked end, a spring urging the other end of said slidably mounted member against the bottom end of said vertical lever, said means for lowering said upper cylindrical member including a pivotally mounted rocker arm carrying a pair of adjustably mounted pawls, said pawls being positioned to successively engage said ratchet teeth as said rocker arm is pivoted, a spring urging said slidably mounted arm into engagement with said pawls, and a handle carried by said slidably mounted arm, whereby said slidably mounted arm may be manually pivoted against the action of said later-mentioned spring to disengage said ratchet teeth from said pawls.

SAMUEL ISAACSON.
